INVENTOR

BY *Victor J. Evans & Co.*

ATTORNEY

UNITED STATES PATENT OFFICE

2,139,600

WRENCH

William A. Parker, Lyles, Tenn.

Application January 25, 1937, Serial No. 122,256

1 Claim. (Cl. 81—118)

This invention relates to wrenches, and its general object is to provide an end wrench that includes pivotally connected companion jaw carrying handle members adjustably associated 5 for movement toward and away from each other, with adjustable reinforcing means bridging the members adjacent to the jaw ends thereof, to limit the outward movement, as well as to strengthen and steady the same, and to relieve 10 undue strain on the threaded adjusting screw of the members, therefore the wrench is capable of performing its intended function without fear of damage to or breakage of the parts.

Another object of the invention is to provide a 15 wrench of the character set forth, that is simple in construction, inexpensive to manufacture and extremely efficient in use, operation and service.

This invention also consists in certain other 20 features of construction and in the combination and arrangement of the several parts, to be hereinafter fully described, illustrated in the accompanying drawing and specifically pointed out in the appended claim.

In describing the invention in detail, reference 25 will be had to the accompanying drawing wherein like characters denote like or corresponding parts throughout the several views, and in which:

Figure 1 is a perspective view of the wrench which forms the subject matter of the present invention.

Figure 2 is a side elevation of the wrench with parts in section and illustrates the degree of taper of the shank portions of the screw for adjusting the jaw members.

Figure 3 is a detail view illustrating the association of the adjusting screw with one of the companion members.

Referring to the drawing in detail, it will be noted that my wrench includes a pair of companion jaw carrying elongated handle members indicated by the reference numerals 1 and 2 and which have flat confronting faces for disposal in contacting engagement with each other, as clearly shown in Figure 1. The members are tapered 45 slightly toward one end, and the member 2 is enlarged as at 3, the enlarged portion being recessed to receive the reduced end 4 of the member 1, and both the enlarged portion and reduced end 4 are provided with openings for a pivot bolt 5, therefore it will be seen that the members are pivotally connected at one end for movement toward and away from each other.

The ends of the members opposed to the pivoted 55 ends are enlarged in curved formation to pro-

vide what may be termed a body 6 for each member, and it will be noted that the outer side faces of the bodies of the members are recessed longitudinally as at 7 in channel formation, to provide a pocket for the outer ends of the adjusting screw 8 which will be presently described, therefore it will be seen from Figure 1, that the threads at the outer ends of the adjusting screw are protected and the flanges provided by the recesses tend to strengthen the jaws.

The body portion of each of the members have threaded bores extending transversely therethrough to threadedly receive the opposed shank portions of the adjusting screw, and it will be obvious that the threads of one shank portion extend in opposed direction to those of the other shank portion, or in other words, right and left hand threads are provided for the shank portions so that upon rotation of the adjusting screw, the members will be moved toward and away from each other.

An adjusting wheel 9 is formed on or otherwise secured to the adjusting screw 8 midway the ends thereof, and the confronting faces of the bodies of the members 1 and 2 are recessed as at 10 to 25 provide pockets for the wheel 9 which is shown as having a serrated periphery to facilitate the rotation thereof as will be apparent, and the front and rear faces of the body portions of the members 1 and 2 are recessed as at 11, with the wheel 30 9 extending therein, so that ready access may be had thereto for rotating the same.

The jaw portions 12 are formed by recessing the free ends of the body portions in substantially rectangular formation, as best shown in Figure 1, 35 and the confronting faces of the jaws are toothed in ratchet formation as at 13, with the teeth extending inwardly, as clearly shown in Figure 1.

In order to limit the outward movement of the handle members 1 and 2, as well as to strengthen 40 the same, and to prevent undue strain on the adjusting screw, I provide a holding means which includes a pair of companion links 14 and 15. The link 14 has its outer end pivotally secured to the member 1, while the link 15 is pivoted to the 45 member 2, and formed on the inner ends of the links 14 and 15 are collars 16, the collar 16 of the link 14 being disposed about the link 15, while the collar of the link 15 is disposed about the link 14 in a manner whereby the links are held associated with respect to each other for slidable movement, as will be apparent upon inspection 50 of Figure 1.

Due to the fact that the free or jaw ends of the members 1 and 2 move in the arc of a circle 55

when being disposed to open or closed positions, as shown in Figures 1 and 2, the shank portions of the adjusting screw 8 are slightly tapered from the adjusting wheel 9 to their outer ends, as best shown in Figure 2, especially by the dot and dash lines, to provide sufficient looseness or play between the threads of the screw and the bores, as best shown in Figure 3, so as to prevent binding of the screw in the bores and free movement thereof, for adjusting the jaws toward and away from each other.

It is thought from the foregoing description that the advantages and novel features of the invention will be readily apparent.

15 It is to be understood that changes may be made in the construction and in the combination and arrangement of the several parts, provided

that such changes fall within the scope of the appended claim.

What I claim is:

An end wrench comprising elongated companion handle members pivotally connected together at one of their ends, jaws at the opposite ends of the handle members, tapered screw means for adjusting the jaws toward and away from each other, links bridging the handle members and having one of their ends pivotally secured thereto, collars on the opposite ends of the links and disposed about the latter for holding the links together for slidable association, and said collars being engageable to limit outward movement of the jaws.

10 WILLIAM A. PARKER.
